UNITED STATES PATENT OFFICE.

JOHN JAY PHARE, OF CLEVELAND, OHIO.

MOP-HOLDER.

1,211,485.

Specification of Letters Patent.

Patented Jan. 9, 1917.

Application filed July 19, 1915. Serial No. 40,544.

To all whom it may concern:

Be it known that I, JOHN JAY PHARE, a citizen of the United States, residing at Cleveland, in the county of Cuyahoga and 5 State of Ohio, have invented certain new and useful Improvements in Mop-Holders, of which the following is a specification.

This invention has reference to a holder for either dry sanitary mops or the ordinary 10 mop manufactured for wet use. Also for oil-treated dusters.

It is to be understood, that the patent herein prayed for is for an improvement upon an invention for which Letters Patent 15 have been granted to the said John Jay Phare under date of March 16, 1915, and numbered 1,182,524, a mop-holder, and the improvement consists in the adaptation of the slotted cross bar, by means of an enlargement 20 at one end of each slot, for the insertion of the heads of rivets disposed at suitable positions in the cross band of the mop, but so attached that the rivet heads protrude from the mop band for engagement 25 with and ready removal from the mop-head slots.

My invention is to obviate a common inconvenience in the attachment of mops to their handles, viz: By the usual methods of 30 attachment the mop proper is drawn within an iron frame-work of the handle so that protruding parts of the holding device come into injurious contact with the wood-work or furniture.

35 The improvement herein shown consists of means of attachment whereby the outer portions of the mop project beyond the holder at each side to form a protecting cushion.

40 My invention will be described in detail hereinafter and illustrated in the accompanying drawings; similar reference characters being used to designate corresponding parts throughout the several 45 views.

Figure 1 is a plan of my device showing the handle in section. Fig. 2 is a cross-sectional view taken horizontally on a line through the two small rivet holes shown in 50 Fig. 3 at the outer ends of upright portion B², said line diverging to intersect the integral clips f. Fig. 3 is a perspective view of device, the handle and mop being broken away. Fig. 4 is a side view of the attaching cross head. Fig. 5 is a modified form

of my device in which the handle and cross-head are made in one piece.

My improvement as shown generally at Fig. 3 consists of a sheet metal stamping B provided with integral clips f punched out 60 and bent to form a socket for the handle A, and so bent at its lower portion as to form a cross bar, Figs. 1 and 2, which is provided with key-hole shaped slots e, adapted at one end to receive the heads of suitable attaching devices h, secured to the transverse band of the mop or duster, symmetrically with the middle portion and at required distances therefrom. When rivets are used for attachment and engagement with holder the 70 rivets are clenched upon small washers at under side of mop band, the heads of rivets protruding above mop to suitably engage in the key-hole slots. Care is to be used that cross-bar is shorter than width of mop 75 to prevent marring of woodwork or furniture by the cross-bar.

Figs. 1, 2, and 3 show the cross-head B comprising a horizontal portion B¹ with slots and an upright portion B² provided 80 with the clamping members f punched out of the crosshead B, and with a reduced upper end bent in arcuate formation, shown also in Fig. 4, adapted to constitute in conjunction with the clamps f a socket for the 85 tapered end of the handle A. I preferably form said mop holder from a sheet metal blank bent into the shape described, though I do not confine myself to this structure.

My invention relates to mop heads for 90 holding sanitary or wet mops such as are in general use, that are usually constructed with a transverse web holding the fibers of the mop together in their middles. At locations in this web, conforming to the key-holed slots in the mop holder cross head heretofore described, I insert rivets h and clinch their points over small washers at the under side of the mop, leaving sufficient of the rivet head protruding from upper 100 side of mop to enter and engage in the slot. In use the rivet heads h are inserted in the apertures e one at a time and the mop adjusts itself in the holder. To remove mop this operation is reversed.

The modified form, Fig. 5, a metal strip doubled together and riveted M, is then bent outward in inverted Y form and at the apertures e'—previously punched out—the ends J are turned inward until they are in 110

line to form the cross-bar. The mop, prepared as above described, may then be attached in like manner.

Having thus described my invention what 5 I claim is:—

1. In a mop holder a head adapted to engage a mop handle, a cross bar comprised in said head having longitudinal slots, one end of each slot having an enlargement to 10 admit the head of a suitable attaching device secured to a mop or duster.
2. A mop holder comprising a head, a cross bar, slots in said cross bar adapted to removably engage the heads of suitable

attaching devices secured to a mop or duster. 15

3. In a mop holder, a head adapted to engage a mop handle and provided with a cross bar, slots in said cross bar and a duster or mop provided with means for engaging said slots whereby the mop or duster is detachably secured to the holder. 20

In testimony whereof I affix my signature in presence of two witnesses.

JOHN JAY PHARE.
